INVENTOR

ATTORNEY

UNITED STATES PATENT OFFICE.

SIDNEY A. FOUCHE, OF FORSYTH, GEORGIA.

BOTTLE.

1,280,700.

Specification of Letters Patent.

Patented Oct. 8, 1918.

Application filed March 10, 1916, Serial No. 83,364. Renewed July 16, 1918. Serial No. 245,238.

To all whom it may concern:

Be it known that I, SIDNEY A. FOUCHE, a citizen of the United States, residing at Forsyth, in the county of Monroe and State of Georgia, have invented certain new and useful Improvements in Bottles, of which the following is a specification.

My invention relates to bottles and contemplates an attachment therefor in the nature of a sanitary measuring cup or glass.

An object of the invention is to so arrange the associated receptacle and bottle that the former may form not only a seal against unauthorized access to the latter but as a positive locking means whereby the bottle stopper is held in place.

I further contemplate a construction and arrangement of parts whereby the trouble and inconvenience incident to dispensation 20 of a predetermined quantity of liquid (more particularly medicine) may be obtained by accurately graduating the receptacle or glass.

A still further object of the invention is to provide an improved means for positively 25 yet removably or detachably fastening the measuring cup or glass over the neck end of the bottle.

The above and additional objects are accomplished by such means as are illustrated 30 in their preferred embodiment in the accompanying drawings, described in the following specification and then more particularly pointed out in the claim which is appended hereto and forms a part of the applica- 35 tion.

In describing my invention in detail reference will be had to the accompanying drawings wherein like characters denote like or corresponding parts throughout the several views, and in which:—

Figure 1 is an elevation of my improved combined bottle and glass.

Fig. 2 is a detailed longitudinal sectional view partly broken away.

Fig. 3 is a top plan view, and

Fig. 4 is an elevation of a modification.

Referring now to the drawings by numerals, 1 designates a bottle equipped with a neck 2 of ordinary construction. An annular horizontally flat shoulder 3 is formed upon the exterior of the bottle adjacent the bottle neck 2, said shoulder providing an abutment for the measuring cup or glass referred to hereinbefore. The bottle 1 and the 55 glass or receptacle 4 are preferably of iden-

tical configuration in cross section, the latter, the glass 4, when mounted to rest upon the shoulder 3, in reality forming a continuation of the bottle to thus present to all outward appearances a part thereof. By such 60 an arrangement it is evident that the annoyance or inconvenience incident to wrapping bottles of ordinary construction is obviated in that a bottle equipped with my improved detachable glass or receptacle, is as above 65 specified, of substantially the same configuration throughout.

The means utilized to releasably fasten said receptacle to the bottle comprises or rather consists of a gum strip or band 5 70 arranged to encircle the bottle at that particular point where said bottle and said glass or receptacle positively engage. The depth of the annular shoulder 3 is preferably equal to the thickness of the material constituting 75 the receptacle 4 that that portion of the bottle merging into the bottle neck will afford a guide for the receptacle leading to said shoulder. Said glass or receptacle, when sealed in the manner stated, will contact (or nearly so) the bottle stopper and, by reason of its proximity thereto, provide a means whereby said stopper is positively rendered inaccessible and incapable of accidental extraction or displacement. 80

As an additional factor in holding the container 4 upon the bottle, I provide a gasket 8 (preferably rubber). Said gasket 8 is arranged at the base of the enlarged portion of the bottle neck whereby to rest 90 upon the shoulder 3 and accordingly snugly engage with the inside of the measuring cup surface.

If desired, a label containing directions, advertising matter, etc., may be fastened 95 upon the bottom of the glass or receptacle 4 (the top of the combined device), diametrically opposed strips 6 being utilized to engage with and fasten the label thereon.

In practice, it is to be understood that 100 the cup or receptacle is to be provided with graduation marks 7 arranged to indicate varying quantities, for instance, when used in connection with a medicine bottle, a teaspoonful, tablespoonful, etc.

From the foregoing, taken in connection with the accompanying drawings it will be noted that a bottle equipped with my improved receptacle may be manufactured and marketed at a nominal cost; said receptacle, 110

before the seal 5 is broken, or thereafter if arranged over the neck 2 of the bottle, will indicate to the user of the contained liquid that such liquid (if medicine) should be taken internally, it being evident that bottles containing medicine to be applied externally would not require or need an associated measuring receptacle 4; and thus as a protective device, the sealed cup or receptacle will preclude fraudulent access to the contents of the bottle and indicate to the purchaser thereof that the contents contained is genuine.

In reduction to practice, I have found that the form of my invention illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

Having thus fully described my invention,

what I claim as new and desire to secure by Letters Patent is:—

30

In combination, a bottle having an annular shoulder formed at the juncture of the body portion and neck thereof, a receptacle adapted to be inverted and placed over the bottle neck with the rim of the receptacle 35 adapted for engagement with the shoulder, a rubber gasket on said shoulder for interposition between the shoulder and the rim of the glass, the exterior of the bottle and receptacle forming a continuous surface, a relatively broad band of rubber encircled about the bottle and designed to overlap the rim of the glass and the portion of the bottle adjacent thereto, said band in conjunction with the gasket forming a seal 45 against the entrance of moisture into the receptacle, and means extending transversely of the band and engaging the bottle and receptacle to secure the receptacle thereto.

50

In testimony whereof I affix my signature in presence of two witnesses.

SIDNEY A. FOUCHE.
